Primary Examiner — Sandra L Morris

(74) Attorney, Agent, or Firm — QuickPatents, LLC;
Kevin Prince(57) **CLAIM**

I claim the ornamental design for a gift card box, as shown and described.

DESCRIPTION

FIG. 1 is a perspective view of a gift card box, showing my new design in an assembled configuration;

FIG. 2 is an exploded perspective view thereof, illustrating a base in a flat position with a central flap in an open position;

FIG. 3 is an exploded front elevational view of FIG. 2, but illustrated with the central flap in a closed position;

FIG. 4 is an exploded rear elevational view of FIG. 3;

FIG. 5 is an exploded right-side elevational view of FIG. 3;

FIG. 6 is an exploded left-side elevational view of FIG. 3;

FIG. 7 is an exploded top plan view of FIG. 3; and,

FIG. 8 is an exploded bottom plan view of FIG. 3.
